UNITED STATES PATENT OFFICE.

JOSEPH DUSEK, OF NEW YORK, N. Y.

TOBACCO-USER'S APPLIANCE.

Application filed December 21, 1920. Serial No. 432,222.

To all whom it may concern:

Be it known that I, JOSEPH DUSEK, a citizen of the United States, residing at New York city, in the county of New York and State of New York, have invented a certain new and useful Improvement in Tobacco-Users' Appliances, of which the following is a specification.

My invention relates to appliances for tobacco smokers.

An important object of my invention is to provide an attachment capable of so physically associating a match-holder with any of the usual containers for cigars, cigarettes or tobacco that the match-holder and the container become one unitary instrument or appliance fulfilling the two related functions of supplying the cigars, cigarettes or tobacco and of supplying the matches for lighting the same.

Another object of my invention is to provide an attachment of such a character that it can be permanently used with successive containers and successive match-holders as such are acquired in replenishing the supplies of cigars, cigarettes or tobacco on the one hand and matches on the other.

Still another object is to provide such an attachment of simple and inexpensive construction.

Other objects of my invention will appear from the detailed description later to be given.

My invention is capable of embodiment in many different forms, and, while I shall illustrate certain specific and preferred embodiments thereof, such embodiments are to be regarded only as typical of many possible embodiments, and my invention is not to be limited to the particular forms illustrated.

Two embodiments of my invention are illustrated in the accompanying drawings: a preferred embodiment in Figs. 1 to 4, inclusive, and a modification thereof in Figs. 5 to 8, inclusive, the preferred embodiment comprising an attachment of two parts foldable to closed position for attachment to the container with which it is to be used and to open position for disassociation from the container.

In the drawings—

Figure 1 is a perspective view of the preferred form of my attachment in closed position and attached to a container for cigars, cigarettes or tobacco, and with a package or folder of matches in the attachment;

Fig. 2 is a longitudinal, sectional view through the container and showing the attachment in open position thereon in side elevational view and partially attached to the container;

Fig. 3 is a longitudinal, sectional view of the container similar to that of Fig. 2, the section being taken on the line 3—3 of Fig. 1, and showing the attachment in side elevational view in closed position as in Fig. 1, and completely attached to the container;

Fig. 4 is a perspective view of the attachment alone and with its foldable parts in open position;

Fig. 5 is a perspective view of the modified form of my attachment, shown as comprising an open or framework casing surrounding a package of cigarettes and having on the face exposed to view, devices for holding the folder of matches there shown;

Fig. 6 is a perspective view of the attachment of Fig. 5 with the package of cigarettes and the folder of matches removed therefrom;

Fig. 7 is a longitudinal, sectional view of the attachment on the line 7—7 of Fig. 6;

Fig. 8 is an elevational view of the lower end of the attachment not exposed to view in Figs. 5 and 6.

Cigarettes and small cigars, or cigarros, are customarily sold, and smoking tobacco is often sold, to the retail trade in small containers of two general types, both adapted to be carried in the pocket of the consumer: one, a rectangular box of relatively unyielding material such as cardboard, and the other a package of substantially the same shape but of yielding material such as paper.

The container 1 in Fig. 1 is intended as an illustration of the first-mentioned type, while the container 1' in Fig. 5 is intended as an illustration of the second-mentioned type, and the form of attachment illustrated in Figs. 1 to 4, inclusive, is particularly

adapted for use with the first-mentioned type of container, while the form of the attachment illustrated in Figs. 5 to 8, inclusive, is particularly adapted for use with the second-mentioned type of container. However, both forms of the invention are capable of use with both types of containers referred to and my invention is not to be understood as restricted in this respect.

10 In the embodiment of the invention illustrated in Figs. 1 to 4, inclusive:

My improved attachment comprises a base 2 of suitable rigid material, preferably metal, cut away as at 3 for economy and 15 lightness, and having side flanges 4 upturned from the base 2.

The material from the rear cut-away portion 3 of the base (see Fig. 4) is upturned to form a vertical flange 5 and an inwardly 20 extending, horizontal ledge 6, the two forming a retaining member for the base portion 7 of the folder of matches, as shown in Fig. 1.

The opposite end of the base portion 2 25 has a central portion upturned therefrom to form a head rest 8 for the flap 9 of the folder of matches.

To the side flanges 4 at their rear extremities are secured plates 10, one for each 30 side flange, from the bottom edge of each of which plates extends a sharp-pointed prong 11.

Intermediate the extremities of the side flanges 4 and preferably substantially nearer the forward than the rear extremities of those flanges, a rod 12 is journaled in the two side flanges, extending across the base portion 2 and a sufficient distance thereabove to permit the insertion between 40 the base portion and the rod of the flap 9 of the folder of matches when that folder is inserted in the holder and to cause the location of the back portion 13 of the folder flat against the base portion 2 of the holder, 45 as shown in Fig. 1.

Secured to the two extremities of the rod 12 projecting outwardly through the side flanges 4, are two levers 14 with their long 50 arms connected by a rod 15. The short arms of the levers terminate in sharp-pointed prongs 16 similar to the prongs 11.

The plates 10 are provided each with a notch 10' in their rearmost or outer extremity, and the long arms of the levers are 55 designed of such a length and the rod 15 is so located thereon that when the arms are folded downwardly toward the base 2 in a folding movement to the rear or toward the plates 10, the inner cylindrical face of the rod 15 first comes into contact with the extremities of the plates 10 above the notches 10' and then by the exertion of a downward pressure on the rod 15, because of the resiliency of the material of the holder, the rod 15 overrides the rear ex-

tremities of the plates 10 and slips into the notches 10', the effect being a spring action permitting the arms 14 to be folded into closed position and thereafter so holding them until a force in a direction to open 70 the lever arms is exerted.

The long arms of the levers 14 are offset at their ends, as shown at 17, to clear the plates 10 in the closed position of the levers, as shown in Figs. 1 and 3.

75 The folder of matches may be inserted in the attachment either before or after the attachment of the holder to the container. To insert the folder, the flap portion 9 is opened and passed between the rod 12 and the base 2 and drawn upward sufficiently to cause the base portion 7 of the folder to extend forwardly beyond the free edge of the ledge 6. Then the folder is moved to the rear to locate its base portion 7 beneath the ledge 6 which, therefore, constitutes a holding device for this base portion of the folder. As the folder is thus adjusted, the matches 18 extend over the rod 12, and to close the folder, the flap 9 80 is folded over the matches and its free edge is inserted beneath the base portion 7 of the folder, in the usual manner.

85 The rearmost prongs 11 extend in a direction to the rear, while the prongs 16 90 on the short arms of the levers 14 extend downwardly in the open position of the levers, as shown in Figs. 2 and 4, and to the front or in a direction opposite to the prongs 11 in the closed position of the 100 levers, as shown in Fig. 3.

95 The short arms of the levers are designed of such a length and the prongs 16 are so located thereon that in the open and vertical position of those levers, as shown 105 in Fig. 2, the ends of the prongs 16 project vertically downward below the base 2 of the attachment, and in the folding of the levers to closed position, the prongs 16 are bodily moved toward the forward end 110 of the attachment, thus increasing the distance between the prongs 11 and 16, as shown in Fig. 4.

To secure the attachment to the container, the levers 14 are moved to the open position and at right angles to the base 2, and maintained in that position while the attachment is bodily manipulated to present the base portion at right angles to the face of the container to which the attachment is to be secured and with the rear prongs 11 toward the container. It is to be observed that the pointed ends of the prongs 11 extend beyond the rear extremity of the plates 10 and the rear, free edge of the base therebetween. In the vertical position of the base of the attachment, therefore, these rear prongs 11 will, upon the exertion of sufficient pressure, penetrate the material of the cover of the container. Upon such

penetration, the base is pivoted downwardly into the position shown in Fig. 2 and pushed rearwardly until the prongs 11 penetrate the cover of the container to their full extent, as also shown in Fig. 2.

In this position, the levers 14 will be substantially vertical, as shown in Fig. 2, and with the prongs 16 extending below the lower face of the base 2 and in position to initially penetrate the cover of the container, which penetration will occur upon the exertion of a sufficient downward pressure upon the attachment. This initial penetration having occurred, the long arms 15 of the levers 14 are folded rearwardly, and in this folding movement the prongs 16 are moved in an arc about the rod 12 as an axis and to the front or away from the prongs 11, thus increasing the distance between the 20 prongs 11 and 16 and the more firmly anchoring the attachment upon the cover of the container by causing the prongs 11 and 16 to penetrate to increasing distances in opposite directions into the material of the 25 container.

The closing of the levers 14 into parallel relation with the base 2 and the snapping of the rod 15 into the notches 10' of the plates 10, completes the operation of securing the attachment to the container.

To remove the attachment from the container, an upward pressure is exerted on the rod 15 to remove it from the notches 10' and thereafter to elevate the levers 14 to a position at right angles to the base of the attachment, as shown in Fig. 2. This opening movement of the levers 14 partially removes the prongs 16 from the material of the container, the complete removal 40 then being accomplished by elevating the forward end of the attachment, when the position shown in Fig. 2 is attained. The prongs 11 are then removed by reversing the movements which inserted them.

In the modified form of the invention illustrated in Figs. 5 to 8, inclusive, an open or framework casing is employed having holding devices for the folder of matches, and within which casing the container for the cigarettes, cigars, or tobacco, is inserted and retained, as shown in Fig. 5, until its contents are consumed, when it is withdrawn and a new container with a new supply is inserted.

Save for its bottom, shown in elevation in Fig. 8, the attachment may conveniently be formed from a single blank of suitable material, preferably metal, and such an attachment is shown in perspective in Figs. 5 and 6.

The attachment comprises a front face, 2', corresponding in function to the base 2 of the embodiment illustrated in Figs. 1 to 4, inclusive, having cut-away portions 3'. Side flanges 4' are upturned from a portion of

the metal of the two longitudinally extending cut-away portions 3' (Fig. 6). A central portion of the material from the rear or bottom cut-away portion 3' (as viewed in Fig. 6), is upturned to form a flange 5' 70 and a forwardly extending ledge 6', substantially parallel with the base 2', the two forming a retaining member for the base portion 7' of the folder of matches, as shown in Fig. 5. A central portion of the 75 material from the forward, or, as viewed in Fig. 6, the upper cut-away portion 3', is upturned to form a head rest 8' for the flap 9' of the folder of matches, as shown in Fig. 5. 80

In the illustrative modification shown, instead of making the side flanges 4' co-extensive with the base as in the first illustrated embodiment, it has been found desirable to shorten these flanges, as shown 85 in Figs. 5 and 6, and to provide just forwardly of them, further upturned portions of the material from the two side cut-away portions 3', in the form of narrow flanges 19 from which extend inwardly and to 90 toward the base 2', narrow fingers 20, functioning as does the rod 12 in the embodiment illustrated in Figs. 1 to 5, inclusive, to hold the back of the folder of matches in place.

As stated, the base of the attachment 95 forms one of its four sides. The three other sides and the front end or top, as viewed in Figs. 5 and 6, are formed from the same blank with the base and have cut-away portions 21 for purposes of 100 economy of material and lightness of weight.

The forward end or top, as viewed in Figs. 5 and 6, likewise has cut-away portions 21 and 22, one of which, 22, preferably extends entirely to the front face or base 2' for the 105 convenient extraction from the container of its contents, as shown in Figs. 5 and 6.

Also formed from the blank are lugs 23, which, when the blank is folded to present the sides and forward end in proper positions in the shape of the box-like structure shown, are bent over the edge of the adjacent sides or ends to hold the parts together.

The rear end or bottom, as viewed in Figs. 5 to 8, inclusive, is closed only by a hinged 115 door 24, having a hook 25 opposite the hinge, fitting by spring action, due to the resiliency of the material of which the holder is composed, over an upturned and rolled flange or lug 26 on the lower end of one of the 120 sides of the holder, as shown in Fig. 7.

The container is inserted into the casing of the attachment through the hinged door, and is secured therein when the pivoted member 24 is closed and latched. The 125 pivoted member 24 in the modification shown in Figs. 5 to 8, inclusive, therefore, performs the same function, so far as the ultimate result of securing the attachment to the container is concerned, as the pivoted 130

member of lever 14 in the form illustrated in Figs. 1 to 5, inclusive.

In the following claims, wherever the words "cigarettes or the like" are used, they are to be understood to cover all tobacco products designed for smoking, including cigarettes, cigars, cigarros, and smoking tobacco.

Having particularly described my invention, what I claim and desire to secure by Letters Patent is:

1. In an attachment of the character described, a base, means for securing a container for matches to one side of said base, and means for securing said base upon its opposite side to the cover of a container for cigarettes or the like.

2. In an attachment of the character described, a base, means for securing a container for matches to one side of said base, and means for detachably securing a container for cigarettes or the like to the opposite side of said base, said last-mentioned means including a member manually operable in effecting said securement and said detachment.

3. In an attachment of the character described, a base, means for securing a container for matches to one side of said base, and means for detachably securing a container for cigarettes or the like to the opposite side of said base, said last-mentioned means including a member operable in one direction of movement in effecting said securement and in another direction in effecting said detachment.

4. In an attachment of the character described, a base, means for securing a container for matches to one side of said base, and means for detachably securing a container for cigarettes or the like to the opposite side of said base, said last-mentioned means including a pivoting member operable in one direction of movement in effecting said securement and in another direction in effecting said detachment.

5. In an attachment of the character described, a base, means for securing a container for matches to one side of said base, and means for detachably securing a container for cigarettes or the like to the opposite side of said base, said last-mentioned means including a member operable in one direction of movement in effecting said se-

curement and in another direction in effecting said detachment, and a latch associated with said member at the completion of its first-mentioned movement.

6. In an attachment of the character described, a base, means for securing a container for matches to one side of said base, and means for securing a container for cigarettes or the like to the opposite side of said base, said last-mentioned means including elements projecting from said base and engaging a portion of said last-mentioned container.

7. In an attachment of the character described, a base having one side adapted to fit against a container for cigarettes or the like, prongs on said base adapted to penetrate a wall of said container against which said base is fitted, and means for securing a container for matches on the opposite side of said base.

8. In an attachment of the character described, a base, means for securing a container for matches to one side of said base, and means for detachably securing a container for cigarettes or the like to the opposite side of said base, said last-mentioned means including elements projecting from said base and relatively movable to increasing distances apart in effecting said securement and to decreasing distances apart in effecting said detachment.

9. In an attachment of the character described, a base, means for securing a container for matches to one side of said base, and means for detachably securing a container for cigarettes or the like to the opposite side of said base, said last-mentioned means including elements manually projectible from said base into engagement with said last-mentioned container.

10. In an attachment of the character described, a base, means for securing a container for matches to one side of said base, and means for detachably securing a container for cigarettes or the like to the opposite side of said base, said last-mentioned means including a lever and an element movable thereby into and out of engaging contact with said last-mentioned container.

In testimony that I claim the foregoing, I have hereunto set my hand this 18th day of December, 1920.

JOSEPH DUSEK.
